UNITED STATES PATENT OFFICE.

WALTER LINDLEY, OF STONE, ENGLAND, ASSIGNOR TO HERMAN C. KUPPER, INC., OF NEW YORK, N. Y., A CORPORATION OF NEW YORK.

DESIGN FOR A COVERED DISH OR SIMILAR ARTICLE.

Application filed November 12, 1928. Serial No. 28,853. Term of patent 7 years.

To all whom it may concern:

Be it known that I, WALTER LINDLEY, a subject of the King of Great Britain, residing in the town of Stone, county of Staffordshire, England, have invented a new, original, and ornamental Design for a Covered Dish or Similar Article, of which the following is a specification, reference being had to the accompanying drawing, forming part thereof.

It is to be understood that in Fig. 1 the ornamentation shown on half of the figure, actually continues throughout the circumference thereof.

I claim:

The ornamental design for a plate or similar article as shown and described.

Signed at the town of Stone, county of Staffordshire, England, this 25th day of October, 1928.

WALTER LINDLEY.
